UNITED STATES PATENT OFFICE.

CHARLIE E. HUBBS, OF STREATOR, ILLINOIS.

UNDERGROUND TROLLEY SYSTEM.

SPECIFICATION forming part of Letters Patent No. 549,920, dated November 19, 1895.

Application filed May 28, 1895. Serial No. 550,403. (No model.)

To all whom it may concern:

Be it known that I, CHARLIE E. HUBBS, a citizen of the United States, residing at Streator, in the county of La Salle and State of Illinois, 5 have invented a new and useful Underground Trolley System, of which the following is a specification.

My invention relates to electric street-railways, and particularly to a trolley system 10 adapted to be arranged below grade or below the plane of the track-rails.

The objects in view are to provide a simple and efficient construction and arrangement of parts whereby a conductor of large cross-sectional area may be employed, to provide simple and efficient means for insulating the conductor to prevent leakage, to provide means for supporting the conductor out of the path of rain and snow admitted through the slot, 20 and, furthermore, to provide efficient means for operating the trolley-pole.

Further objects and advantages of this invention will appear in the following description, and the novel features thereof will be particularly pointed out in the appended claims.

In the drawings, Figure 1 is a transverse section of a road-bed constructed in accordance with my invention. Fig. 2 is a detail view in perspective of one of the castings which combine to form the conduit. Fig. 3 is a detail view of the joint between the ends of two connected sections of the conductor. Fig. 4 is a side view of the means for operating the trolley pole or arm, a portion of the road-bed being shown in section to indicate the manner of mounting the trolley-wheel. Fig. 5 is a detail view of the means for guiding the trolley-arm.

Similar numerals of reference indicate corresponding parts in all the figures of the drawings.

Arranged upon horizontal transverse ties 1 is a cement bed 2, the center of which is depressed to form a drain-basin 3, which communicates by means of suitable piping 4 with a sewer (not shown) whereby water entering the conduit is carried off and prevented from accumulating therein. Resting upon the cement bed 2 are transversely-opposite castings 5 and 6, provided at their outer ends with ears 7, which are bolted to the webs 8 of the rails 9, said rails having their bases resting upon

the upper surface of the cement bed. These castings comprise horizontal bases 10, webs 11, and concave flanges 12, the flanges 12 of the 55 opposite castings having their concave faces arranged to connect with or merge into the concave surface of the basin 3. The lateral ears 13, which are flush with the upper edges of the webs of the castings, support road- 60 plates 14 and 15, which are bolted thereto, the plates 14, which are arranged upon one side of the slot 16, being provided at intervals with hinged sections 17, whereby access to the interior of the conduit may be had for the 65 purpose of repairing the conductor or cleaning the conduit. The casting 5 comprises a main or body portion or section and a removable or auxiliary section 18, the contiguous ends of said main and auxiliary sections being provided with ears 19, connected together by bolts 20, and in the contiguous edges of the main and auxiliary sections is formed a seat 21 for the conductor 22, said conductor corresponding approximately in cross - sec- 70 tion with a T - rail and having a flanged base 23, a web 24, and a tread or head 25, the latter being preferably of copper. Interposed between the base of this conductor, which is arranged in the upwardly-flared or 75 dovetailed seat 21, and the seat is an insulator 26, preferably formed of glass. The slot 16, being formed between the outer extremity of the auxiliary section 18 and the contiguous end of the casting 6, is removed 80 laterally from the plane of the conductor a distance sufficient to prevent water entering the slot from coming in contact with the conductor, and also to prevent objects inserted through the slot from the exterior from touch- 85 ing the same. The lower or free edges of the insulator 26 are flared outwardly toward their lower extremities, as shown at 27, to act as guards, and the auxiliary section 18 of the casting 5 is provided between its inner extremity and the seat 21 with a depending drip-point 28 to prevent water running down the face of the casting from passing inward beyond said point.

The trolley-arm 29 extends vertically downward into the conduit and is provided with a horizontal extension 30, terminating in up-standing ears 31, in which are mounted the trunnions of the trolley-wheel 32. Said trun-

nions are mounted in bearing-blocks 33, which are fitted to slide in vertical slots 34 in the ears, tension-springs 35 being employed to cause the wheel to follow any irregularities 5 of the conductors without jarring or straining the trolley-arm. The conductor is preferably formed in sections provided with halved or rabbeted extremities, as shown at 36, said ends being preferably soldered and 10 riveted together.

The trolley-arm is provided with a rack 37 and is fitted in a guide 38, having a removable face-plate 39, said face-plate being held in place by means of keyhole slots 40 formed 15 therein engaging headed studs 41 at the sides of the guide. Engaging said rack is a pinion 42, to which are secured sprocket-wheels 43, engaged by endless chains 44. By means of these chains motion may be communicated 20 in either direction to the trolley-arm by means of the operating spindles 45.

From the above description it will be seen that a heavy conductor may be employed, and that when arranged in the seats provided for 25 its reception in the conduit it is protected from contact with foreign substances introduced through the slot. It will be seen, furthermore, that any desired section of the conductor may be removed and replaced when 30 necessary, and that the mounting of the conductor in the seats is facilitated by the removable section of the casting, between which and the main section of the casting the seat 35 is formed.

35 The hinged portion 17 of the road-plate rests upon the castings, and the conductor is supported solely by the castings. The hinged sections 17 are preferably arranged contiguous to every other or alternate castings, and 40 in practice the insulating material may be arranged upon the alternate or intermediate castings.

45 The feed-wire 46 is arranged in the aligned openings of the castings 11 at one side of the conduit, and the return-wire 47 is arranged in the aligned openings of the other casting, and the return-wire should be tapped to the rail at intervals corresponding with those at 50 which the feed-wire is tapped to the conductor or trolley-wire. Said feed and return-wires are insulated throughout and are supported by pins 48, having suitable insulating-seats 49, through which the wires extend.

55 In practice various changes in the form, proportion, and the minor details of construction may be resorted to without departing from the spirit or sacrificing any of the advantages of this invention.

Having described my invention, what I 60 claim is—

65 1. A conduit for underground trolley systems, having transverse ties, a cement bed supported by the ties and having a centrally depressed drain-basin connected with a drain-pipe, sets of opposite castings cut away at their inner ends above said basin and terminating contiguous to each other to form a slot,

track rails seated upon said cement bed near its lateral edges and connecting the outer extremities of the castings in series, road-plates 70 resting upon the upper edges of the castings between the vertical planes of the track rails, and a conductor supported by the castings upon one side of the slot and within the space between the cut-away inner ends of the castings, substantially as specified. 75

2. A conduit for underground trolley systems, having a horizontal bed and a centrally depressed drain-basin, sets of opposite castings seated upon said bed and cut away at 80 their inner ends to form an intervening space above the basin, the upper edges of the castings terminating contiguous to each other above said space to form a continuous slot, road-plates supported by the castings, track 85 rails connecting the outer ends of the castings and extending from the road-bed to the lower edges of the castings, a conductor arranged in the space between the cut-away ends of the castings out of the vertical plane 90 of the slot, and feeders arranged in horizontally registering openings formed in the castings between the cut-away inner ends and the planes of the track rails, substantially as specified. 95

3. A conduit for electric railways formed by the combination of sets of opposite castings connected by track rails bolted to their outer extremities and separated at their inner ends to form a continuous slot for a trolley arm, road-plates bolted to the upper edges of the castings, said plates being provided at intervals with hinged sections to provide access to the conduit, and seats being formed in the castings out of the vertical plane of the slot 105 and beneath said hinged sections of the road-plates, and conductors arranged in said seats, substantially as specified.

4. A conduit for electric railways comprising a chamber and a slot communicating with the chamber, a conductor arranged in the upper portion of the chamber at one side of the plane of the slot, an arm in electrical contact with the motor of a car and extending through the slot into the chamber, said arm 110 being provided with current-transmitting means for contact with the conductor, a guide for said arm having an open side through which the arm may be inserted and removed, a removable face-plate covering the open side 115 of the guide and provided with elongated slots engaging headed studs on the guide, and means for communicating motion to the arm to arrange the current-transmitting devices 120 in or out of contact with the conductor, substantially as specified. 125

In testimony that I claim the foregoing as my own I have hereto affixed my signature in the presence of two witnesses.

CHARLIE E. HUBBS.
